UNITED STATES PATENT OFFICE.

REUBEN C. HIGGINS AND ABRAHAM FULLER, OF BOSTON, MASSACHUSETTS.

IMPROVED CARPET-SWEEPER.

Specification forming part of Letters Patent No. 96,807, dated November 16, 1869.

To all whom it may concern:

Be it known that we, REUBEN C. HIGGINS and ABRAHAM FULLER, both of Boston, in the county of Suffolk and Commonwealth of Massachusetts, have made an invention of a certain new and useful Improvement in Carpet-Sweepers for Household Purposes; and we do hereby declare the following to be a full, clear, and exact description thereof, due reference being had to the accompanying drawings, making part of this specification, and in which—

Figure 1 is an under side perspective representation, Fig. 2 a longitudinal and vertical section, and Fig. 3 a vertical and transverse section, of a carpet-sweeper embodying our invention.

The invention herein described, and which constitutes the subject-matter of this patent, is of that class of carpet-sweepers in which the revolution of the brush is effected by a gear and pinion, the former being swiveled to the case or box of the implement, and bearing upon the carpet from which it derives motion and power, and the latter fixed to the brush-shaft and receiving motion from the former, which meshes into it, the brush, as in all carpet-sweepers, being a cylindrical one, and operating in connection with two pans or troughs applied longitudinally of the case of the implement in such manner that the dirt, by the revolution of the brush, is deposited therein. It becomes necessary to apply the plate in which the shaft bearings or steps are formed adjustably to the case of the implement, to compensate for the wear of the brush and for other causes. A serious evil found to exist in practical and continued use of the present sweepers is tendency of lint and other dirt to collect and accumulate about and between the teeth of the gear and pinion, frequently stopping their motion entirely and always retarding their perfect action.

This invention is intended to obviate these objections; and it consists in the peculiar formation of the trundle or driving gear, whereby the tendency to clog is entirely avoided and the sweeper propelled over the carpet in an easy and comparatively frictionless manner.

The drawings before mentioned as accompanying this specification, and which illustrate our invention, represent a carpet-sweeper as composed of an oblong rectangular box or case, A, open at its bottom, and at top provided with

a suitable cover, B, for inspection or removal of its contents of dirt and refuse taken up by the brush, such dirt being deposited in two troughs or pans, a a, extending from end to end of the box, and bearing upon the surface of the carpet, or in close proximity thereto, after the manner of sweepers of its class.

The cylindrical brush is shown at b and its shaft at c, the journals of such shaft being supported in bearings formed in metallic plates d d, applied adjustably to the opposite outer ends of the case A.

The above parts are constructed and arranged in manner similar to many carpet-sweepers, and so far possesses no points of novelty peculiar to ourselves.

We apply to each end of the box A a short immovable stud or journal, e, projecting laterally from it and over the bearing-plate of the brush-shaft, and to such studs we pivot the prongs or arms f f of the fork of the handle, as shown at g. By this means the handle is removed from contact with the brush-shaft and the latter is isolated from injurious action of the former.

The trundle and driving gear of the implement is shown at i in the drawings as mounted and revolving upon a short horizontal shaft, k, projecting inwardly from a metallic plate or bar, l, fixed in an adjustable manner to the outside of one end of the box A, in order that the relative position of the gear may be varied to accommodate it to the lowering of the brush and its pinion under wear of such brush. This trundle-gear i is a compound one and of peculiar formation—that is to say, it has a serrated, fluted, or abraded periphery, to adhere tenaciously to the carpet, and by which means a driving-power is obtained to propel the machine and revolve the brush; and it also has a series of isolated teeth or pins, m m, &c., projecting laterally from its inner side and in a regular circular concentric path, the aggregate periphery of these teeth or pinions being considerably less than that of the gear, in order to remove them from contact with the carpet.

To aid the locomotive of the sweeper over the carpet, I pivot a wheel, n, in size, manner, and disposition similar to the gear, but upon the opposite side of the brush, and with a smooth periphery.

The pinion, or, more strictly speaking, sprocket-wheel, affixed to the brush-shaft is

shown at *o* in the drawings as of such size and disposition that the pins *m m* of the trundle-gear *i* shall mesh into and impart revolution to it and the brush. The nature and disposition of these pins *m m*, isolated as they are, in comparison to the teeth of gears, entirely prevent any collection and accumulation of lint or other refuse matter or dirt, and, as before observed, in this respect produce a very important result.

What we claim is—

The construction and arrangement, with the case of the carpet-sweeper, of the adjustable brush-shaft and its driving-pinion and the trundle-gear *i*, in the manner shown and described.

REUBEN C. HIGGINS.
ABRAHAM FULLER.
